(57) **CLAIM**

The ornamental design for a coupler follower for selective cushioning unit, as shown and described.

DESCRIPTION

FIG. 1 is a perspective view thereof;

FIG. 2 is a front elevation view thereof;

FIG. 3 is a rear elevation view thereof;

FIG. 4 is a side elevation view;

FIG. 5 is a side elevation view which is a mirror of the opposite side elevation of FIG. 4;

FIG. 6 is a top view thereof; and,

FIG. 7 is a bottom view thereof.

The portion of the drawings in FIG. 3 and FIG. 7 bounded by dotted lines forms no part of the claimed design.

1 Claim, 3 Drawing Sheets
